United States Patent

Des. 235,807
Patented July 8, 1975

235,807

PRINTING PRESS

John R. Krutsch, Glenview, Ill., assignor to American
Screen Printing Equipment Company, Chicago, Ill.

Filed Nov. 19, 1973, Ser. No. 416,924

Term of patent 14 years

Int. Cl. D18—02

U.S. CL. D64—11 R

FIG. 1 is a front elevational view of a printing press showing my new design;

FIG. 2 is a side elevational view of the printing press shown in FIG. 1, the opposite side being substantially similar; and

FIG. 3 is a top plan view of the printing press shown in FIG. 1.

FIG. 4 is a rear elevational view thereof.

I claim:

The ornamental design for a printing press, as shown.
